DRILLING ATTACHMENT FOR METAL-
WORKING MACHINES

George F. Yager and Oliver J. Heath, Toledo,
Ohio, assignors to The Bunting Brass & Bronze
Company, Toledo, Ohio, a corporation of Ohio

Application January 22, 1934, Serial No. 707,790

4 Claims. (Cl. 77—32)

This invention relates generally to drilling machines and refers more particularly to drilling attachments for metal working machines of the type set forth in our application, Serial No. 5 639,354, filed October 24, 1932.

One of the essential objects of the present invention is to provide a drilling attachment of the type described that may be readily applied to the frame of such a metal working machine 10 preferably in place of or as a substitute for the milling attachment set forth in said application and that may be operatively associated with appropriate driving elements of such a machine.

Another object is to provide a drilling attachment 15 wherein provision is made for adjusting the drilling element vertically, horizontally and angularly relative to the work.

Another object is to provide a drilling attachment wherein the drilling element is moved by 20 yieldable means toward and into the work and is moved by cam means out of and away from the work.

Another object is to provide a drilling attachment wherein the cam just mentioned for moving 25 the drilling element is alternately actuatable by a coil spring and by parts operatively associated with the driving elements aforesaid of the metal working machine.

Another object is to provide a drilling attachment 30 wherein the coil spring and parts just mentioned are connected in such a way that the spring is wound up by said parts while they are actuating the cam.

Other objects, advantages and novel details of 35 construction of this invention will be made more apparent as this description proceeds, especially when considered in connection with the accompanying drawings, wherein:

Figure 1 is an end elevation of a metal working 40 machine with a drilling attachment embodying our invention applied thereto showing parts broken away and in section;

Figure 2 is an enlarged fragmentary elevation 45 of the structure illustrated in Figure 1 with parts broken away and in section;

Figure 3 is a view taken at substantially right angles to Figure 2;

Figure 4 is a vertical sectional view taken substantially on the line 4—4 of Figure 2;

Figure 5 is a horizontal sectional view taken 50 substantially on the line 5—5 of Figure 3;

Figure 6 is a horizontal sectional view taken substantially on the line 6—6 of Figure 3;

Figure 7 is a perspective view of the bracket C;

Figure 8 is a perspective view of the body F;

Figure 9 is a perspective view of the plate B; 5 Figure 10 is a perspective view of the bearing 35;

Figure 11 is a view similar to Figure 2, but showing a slight modification;

Figure 12 is a view taken at substantially right angles to Figure 11;

Figure 13 is a vertical section taken substantially on the line 13—13 of Figure 11;

Figure 14 is a horizontal sectional view taken 10 substantially on the line 14—14 of Figure 11;

Figure 15 is a perspective view of the bracket L; 15 Figure 16 is a perspective view of the plate M; Figure 17 is a perspective view of the bracket K; Figure 18 is a perspective view of the bracket J. 15

Referring now to the drawings, A is the frame 20 of a metal working machine of the type illustrated in our application, Serial No. 639,354, aforesaid, B is a plate adjustable horizontally on said frame, C is a bracket adjustable horizontally 25 on the plate B in a direction substantially at right angles to the direction in which the plate B is adjustable, D is an upright plate pivoted on a pin E projecting laterally from the frame A and movable in an arc over an upstanding portion 1 of the bracket C, and F is a body adjustable vertically on the plate D and having horizontally and vertically projecting portions 2, 3 and 4, respectively.

As shown, the plate B is recessed at 25 to receive a horizontal rib 6 of the frame A and 30 is provided at opposite edges thereof with spaced elongated slots 7 that receive suitable attaching means such as the bolts 8 which engage the frame A. Any suitable means such as the screw 9 journaled in an upstanding bearing 10 on the 35 frame A and threadedly engaging the plate B may be used as the means for adjusting said plate on the rib 6 of the frame. Extending between the slots 7 and disposed at substantially right angles thereto are parallel keyways 11 which 40 receive suitable keys such as 12. The base 13 of the bracket C has corresponding keyways 14 therein registering with the keyways 11 and receiving the keys 12. Preferably an adjusting screw 15 similar to 9 is employed for moving the 45 bracket C on the plate B. As shown, the screw 15 is journaled in a sectional bearing 17 fastened to an edge of the plate B and threadedly engages the base 13 of the bracket C. Any suitable means such as bolts 18 carried by the plate B and engaging elongated slots 19 and the base 13 may 50 be used to hold the parts together. The upstanding portion 1 of the bracket C is disposed at substantially right angles to the base 13 and is preferably reinforced by vertical and horizon-

55

tal webs 20 and 21, respectively. The front face 22 of the upstanding portion 1 is flat so as to facilitate movement thereover by the plate D, while the upper edge 23 of said upright portion 1 is preferably curved and provided with suitable graduations 24. The upstanding portion 1 of the bracket is also provided with upper and lower rows of elongated slots 25 which are preferably arranged in arcs concentric with the pivot pin E. The upright plate D is elongated in form and has a flat rear face 26 engaging the flat face 22 of the bracket C. Any suitable means such as the bolts 27 extending through the slots 25 in the upstanding portion 1 of the bracket C and threadedly engaging the plate D may be used to connect the plate D to the bracket and to hold such plate in adjusted position on the pivot pin E. The front face 28 of the upright plate D is preferably parallel to its rear face 26 and is provided with parallel longitudinally extending keyways 29, while the upper end 30 of said plate is slightly arcuate and is preferably provided at the inner edge with a graduation or mark 31 for use in connection with the graduations 24 on the upper edge of the bracket C. The body F is provided in its rear face with parallel keyways 32 corresponding to and registering with the keyways 29 in the front face of the upright plate D. Any suitable means such as the keys 33 in said registering keyways may be used to guide the body F longitudinally of the plate D, while any suitable means such as a screw 34 journaled in a sectional bearing 35 upon the upper end of the plate D and threadedly engaging the body F may be used to effect such an adjustment. Preferably the rear face of the body F is recessed at 36 below the threaded portion 37 thereof for the reception of the screw 34.

In the present instance, the horizontally extending portion 2 of the body extends over a rotary work dial or turret H of the metal working machine, while the horizontal portion 3 projects laterally from the body and is disposed at substantially right angles to the portion 2. The vertically extending portion 4 of the body is above and at the rear end of the horizontal portion 2.

Preferably the work dial H corresponds to the turret B in our application, Serial No. 639,354, and is provided in its periphery with suitable recesses 40 in which the work such as bushings or bearings 41 may be carried. Any suitable means (not shown) may be used to rotate the dial H. Preferably the same means as that illustrated in our application, Serial No. 639,354, is used, however, such means forms no part of the present invention.

41' is a quill slidably mounted in a vertical opening 42 in the horizontal portion 2 of the body, 43 is a spindle rotatably mounted within the quill 41', 44 are ball bearings for the spindle 43, 45 and 46 respectively are inner and outer races for said ball bearings, 47 and 48 respectively are retaining nuts for said races 45 and 46, 49 is a chuck of standard design fixed to the lower end of the spindle 43 below the nuts 47 and 48, and 50 is a drill carried by the chuck 49 and engageable with the work 41 in the dial H. Preferably the construction is such that the work 41 is in proper position to be engaged by the drill 50 when the center 51 of each recess 40 in the dial H is coincident with the axes of the pivot pin E and drill 50. (See Figure 2).

53 is an electric motor mounted on the vertically extending portion 4 of the body and having a short shaft 54, 55 is a drive shaft sleeved

upon and fixed to said motor shaft 54 and extending axially and splined to the walls of an upwardly opening socket 56 in the spindle 43.

In the present construction the drill 50 is moved downwardly toward and into the work 41 by a coil spring 57 and is withdrawn and moved upwardly from the work by a cam 58. As shown, the spring 57 is received in a vertical opening 59 in the horizontal portion 2 of the body and seats upon the upper face of a collar 60 clamped upon the quill 41 at the lower end thereof. A top plate 61 on the horizontal portion 2 serves as a closure for the upper end of the opening 59 and as a backer for the upper end of the spring 57 and receives and carries a suitable seal 62 for the drive shaft 55. The cam 58 is fixed to a shaft 63 journaled in a bracket 64 secured to the horizontal portion 3 of the body and is engageable with a roller 65 on a stud 66 projecting laterally from a block 67 secured to the quill 41'. As shown, this block 67 is movable vertically in an elongated slot 68 in the horizontal portion 2 of the body.

69 is a pinion fixed to the shaft 63 and meshing with a gear sector 70 fixed to a shaft 71 journaled in the bracket 64 and in a cylindrical portion 72 of the body. Sleeved on and adjustably secured to a lateral projection 73 of the gear sector 70 is a collar 74, while sleeved on the lateral projection 73 between and terminally secured to said collar 74 and cylindrical portion 72 is a coil spring 75 for moving the gear sector 70 in an anti-clockwise direction so that the cam 58 will move in a clockwise direction and let spring 57 move the drill 50 downwardly toward and into the work 41.

Sleeved upon and fixed to the shaft 71 at the outer end thereof is a tubular portion 77 of a friction clutch element 78, while sleeved on the tubular portion 77 between an adjusting nut 79 and the clutch element 78 is a pulley 80 having a clutch face 81 engaging the clutch face 82 of said element. Fixed to the pulley 80 is a cable 83 having an eye 84 at its lower end receiving a hook 85 pivotally connected to an arm 86 of a bell crank lever 87 corresponding to lever 210 in our application, Serial No. 639,354, and pivotally mounted at 88 upon the frame A of the metal working machine. Preferably this lever 87 carries a roller 89 which engages a cam 90 on the cam shaft 91 of the machine and is held in such engagement by a coil spring 92 secured to the frame A.

In use, the drill 50 may be adjusted in a horizontal plane forwardly and rearwardly relative to the work 41 in the dial H by turning the screw 9 and may be adjusted in a horizontal plane tangentially to the dial by adjusting the screw 15. To compensate for short and long drills, the body F may be raised or lowered on the upright plate D by loosening and tightening the bolts 93, while the plate D may be swung on its pivot pin E upon adjustment of the bolts 27 to incline the drill 50 relative to the work for drilling inclined holes in said work. The drill 50 will be rotated during rotation of the motor shaft 54 regardless of the position of the drill relative to the work 41 due to the splined connection between the spindle 43 and drive shaft 55. When the bell crank arm 86 is moved upwardly, the coil spring 75 will turn the gear sector 70 anti-clockwise and thus cause cam 58 to let spring 57 move the drill 50 downwardly into the work in the dial H. When the bell crank arm 86 is moved downwardly, the cable 83 will turn the shaft 71 and gear sector 70 clockwise and will cause coil spring 75

to be wound up and cam 58 to be moved in an anti-clockwise direction. As a result, cam 58 will raise the quill (41') and cause the drill 50 to be withdrawn from the work to its raised position. Of course the dial H will be rotated in timed relation to the movements of the bell crank lever 87 so that the work 41 will be in proper position each time the drill 50 is lowered by the spring 57. Any suitable mechanism such as that illustrated in our application, Serial No. 639,354, may be used for this purpose. Moreover, the nut 79 and collar 74 may be adjusted as desired to compensate for any timing irregularities or variations in spring tension. Likewise, the cam 58 15 may be removed and replaced by other cams of different sizes when it is desired to vary the stroke of the drill 50 relative to the work.

In Figures 11 to 18, inclusive, we have illustrated a slight modification in which the drill 50^a is horizontally disposed instead of vertically and is engageable with the work 41 when it is at one side instead of at the top of the dial H. In detail, J is a bracket fixed to the frame A of the machine, K is a bracket adjustable vertically on the bracket 25 J, L is a tilting bracket pivotally connected to the bracket K, M is a plate adjustable horizontally on the tilting bracket L in a direction transverse to the dial H, and N is a body adjustable horizontally on the plate M toward and away from the dial H. 30 Preferably the opposed faces 103 and 101 respectively of the brackets J and K are flat and have registering keyways 102 and 103 therein receiving a suitable key 104. Any suitable means such as a screw 105 threadedly engaging a stud 106 fixed to 35 the frame A and bearing against the lower face of the bracket K may be used to raise the said bracket. Bolts 107 threadedly engaging the bracket J and slidably engaging elongated slots 108 in the bracket K, cooperate with bolts 109 threadedly engaging the bracket K and slidably 40 engaging elongated slots 110 in the bracket J to hold the parts together. As shown, the bracket K straddles the bracket L and is preferably provided with a graduation or mark 111 for use in connection with graduations 112 on the bracket L when 45 the latter is adjusted about its pivot 113. In this connection, it will be noted that the pivot 113 is carried by the bracket K and that in addition to bolts 114 threadedly engaging the bracket sides 50 115 and 116 respectively and slidably engaging elongated slots 117 in opposite sides of the bracket L, a turnbuckle 118 is terminally connected to studs 119 and 120 respectively, rigid with said parts. Preferably an enlargement 121 of the bracket K serves as an abutment for the screw 105 and receives the stud 119. The opposed faces 55 of the bracket L and plate M have registering keyways 118' and 119' respectively which receive keys 122 for guiding the plate M, and a screw 123 journaled in a bearing 124 and threadedly engaging the plate M is preferably used as adjusting means 60 for said plate. Preferably the bearing 124 is rigid with one side of the bracket L and is received in an upwardly opening slot or recess 125 in the bracket K. The opposed faces of the plate M and body N also have registering parallel keyways 126 65 and 127 receiving keys 128 for guiding the body N, and the adjustment of said body on said plate is preferably accomplished by a screw 129 journaled 70 in a bearing 130 fixed to the rear edge of the plate M and threadedly engaging the body. In this construction an electric motor 131 is carried by a horizontal portion 132 of the body in line with the drill 50^a, but the drive between the parts is the same as in Figures 1 to 10, inclusive. The quill 75

133 to which the chuck 134 is secured is moved toward and into the work by a coil spring 135 and is moved out of and away from the work by a cam 136. As shown, the spring 135 is received in the horizontal opening 137 in the body and terminally 5 engages a collar 138 on the quill and an end plate 139 on the body, while the cam 136 is fixed to a shaft 140 journaled in a bracket 141 fixed to the body and is engageable with a roller 142 carried by a block 143 fixed to the quill. A pinion 144 is fixed 10 to the shaft 140 and meshes with a gear sector 145 fixed to a shaft 146 journaled in aligned openings in the body N and bracket 141. A coil spring 147 is sleeved on a tubular projection 148 of the gear sector and is terminally secured to the body N 15 and to a collar 149 adjustable on the projection 148. Sleeved upon and fixed to the shaft 146 at the outer end thereof is a tubular portion 150 of a friction clutch element 151, while sleeved on the tubular portion 150 between an adjusting nut 152 20 and the clutch element 151 is a pulley 153 having a clutch face 154 engaging the clutch face 155 of said element 151. Fixed to the pulley 153 is a cable 156 having an eye 157 at its lower end receiving a hook 158 pivotally connected to the arm 86 of the 25 bell crank lever 87.

In use, the drill 50^a may be adjusted in a horizontal plane forwardly and rearwardly relative to the work 41 in the dial H by turning the screw 129 and may be adjusted in a horizontal plane transversely of the dial by adjusting the screw 123. The body N may be raised or lowered on the bracket J by turning the screw 105 after the bolts 107 and 109 have been loosened, and may be swung about the pivot 113 upon adjustment of the turnbuckle 118 to incline the drill 50^a relative to the work for drilling inclined holes. When the bell crank arm 86 is moved upwardly, the coil spring 147 will turn the gear sector 145 anti-clockwise and thus cause cam 136 to let spring 135 move the 40 drill 50^a into the work 41 in the dial. When the bell crank arm 86 is moved downwardly, the cable 156 will turn the shaft 146 and gear sector 145 clockwise and will cause coil spring 147 to be wound up and cam 136 to be moved in an anti-clockwise direction. As a result, the quill 133 will be moved to the right and will thus cause the drill 50^a to be withdrawn from the work to its retracted position. Of course the dial H will be rotated in timed relation to the movements of the bell crank lever 87 so that the work will be in proper position each time the drill is moved to the left by the spring 135. Any suitable mechanism such as that illustrated in our application, Serial No. 639,354, may be used for this purpose. 55

What we claim as our invention is:

1. In a drilling machine, a work holder, a drill spindle movable longitudinally toward and from work in said holder, a cam mounted to oscillate in opposite directions, means including a spring 60 for turning the cam in one direction, means for positively turning the cam in the opposite direction against the tension of said spring, means including a spring operable when the cam is turned in the first mentioned direction to feed the drill 65 to work in said holder, and a cam follower operable by the cam when it is turned in the second mentioned direction to retract the drill from the work.

2. In a drilling machine, a work holder, a drill spindle movable longitudinally toward and from work in said holder, a cam mounted to oscillate in opposite directions, means for turning the cam in one direction, said means being yieldable to permit turning movement of said cam in the opposite 75

direction, means for positively turning the cam in the opposite direction, said last mentioned means being reversible to permit movement of the cam in the first mentioned direction, the first and second means just mentioned being operable alternately for actuating said cam, means including a spring operable when the cam is turned in the first mentioned direction to feed the drill to work in said holder, and a cam follower operable by the cam when it is turned in the second mentioned direction to retract the drill from the work.

3. A drilling attachment for a metal working machine having a work holder, comprising a quill movable toward and from the work holder, a cam operable to positively move the quill away from the work holder, a shaft for said cam, a second shaft substantially parallel to the first mentioned shaft, a driving connection between said shafts, a first spring for yieldingly turning the second mentioned shaft in one direction so that the quill will be released by said cam, a second spring operable when the quill is released by said cam to yieldingly feed the quill toward the work holder, and means subsequently operable to wind up the first spring and positively turn the second shaft

and cam in the opposite direction so that the quill will be positively retracted from the work holder.

4. In a drilling machine having a work holder, a rotating drill spindle movable toward and from said work holder, a support for said spindle including a reciprocating quill having two projections at spaced points thereof, actuating means for the quill including a first spring and a cam, said first spring being engageable with one of said projections for yieldingly feeding the drill spindle toward the work holder, and said cam being engageable with the other of said projections to positively retract the drill spindle from the work holder, said cam being oscillatable in one direction to retract the spindle and in the opposite direction to permit the feeding of the spindle by said first spring, and actuating means for the cam including a second spring and a rotary element, the rotary element being operable to turn the cam in the first mentioned direction, and said second spring being operable to turn the cam in the second mentioned direction.

GEORGE F. YAGER.
OLIVER J. HEATH.
